(57) **CLAIM**

The ornamental design for an animal hair clipper, as shown and described.

DESCRIPTION

FIG. 1 is a top perspective view of an animal hair clipper, showing my design.

FIG. 2 is a bottom perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof.

FIG. 9 is an enlarged view of an area labeled 9 in FIG. 1.

FIG. 10 is an enlarged view of an area labeled 10 in FIG. 1; and,

FIG. 11 is an enlarged view of an area labeled 11 in FIG. 2. The broken lines shown in FIGS. 1, 2, 9, 10 and 11 represent the boundaries and indicators of the enlarged views. The broken lines form no part of the claimed design.

1 Claim, 11 Drawing Sheets
